UNITED STATES PATENT OFFICE

2,604,894

HAIR CURLER

Grace A. Broyles, Kenosha, Wis.

Application October 17, 1950, Serial No. 190,550

3 Claims. (Cl. 132—42)

1

This invention relates to new and useful improvements and structural refinements in hair curlers, particularly hair curlers of the type adapted to be worn on the hair after having a lock of hair wound and secured thereon, the principal object of the invention being to provide a hair curler which combines features of comfort and convenience.

Of course, in hair curlers of conventional type an effort was made to achieve these features, but such efforts were not successful since the features were present independently rather than in combination. In other words, if the curler was made soft enough for comfort, it was not sufficiently firm to be durable and conveniently practical. On the other hand, if the curler was made firm enough to be practically convenient, it was not soft enough to be comfortable, particularly when slept on.

The instant invention, therefore, eliminates these disadvantages by providing a curler which is firm yet comfortable, which is durable yet flexible and resilient and which, by virtue of these characteristics, is capable of automatically adjusting itself to the hair and head of the user, particularly when the latter changes position of her head during sleep, so that in effect, the soft, flexible and resilient nature of the curler is soothing and comforting and thereby inducive to sleep.

The above features are achieved primarily by embodying in the construction of the curler a cushion of what is commonly called "air-foam" or "foam" rubber, this being encased in thin plastic material, the foam rubber cushion together with its plastic enclosure being folded so as to provide a plurality of pads around which a strand of hair may be wound and thereafter secured by employing novel securing means.

Some other advantages of the invention reside in its simplicity of construction, in its moisture-proof, sanitary nature, in its pleasing appearance which renders it adaptable for casual or sportswear as well as for use while sleeping, in its adaptability to economical manufacture and, above all, in its adaptability for convenient and expeditious use.

With the above more important objects and features in view and such other objects and features as may become apparent as this specification proceeds, the invention consists essentially of the arrangement and construction of parts as illustrated in the accompanying drawings, in which:

Figure 1 is a group perspective view of the components of the invention;

2

Figure 2 is an edge view of the hair curler in its open position;

Figure 3 is a perspective view of the hair curler in its closed position, the same being shown applied to a strand of hair; and

Figure 4 is a transverse sectional detail, taken substantially in the plane of the line 4—4 in Figure 3.

Like characters of reference are employed to designate like parts in the specification and throughout the several views.

Referring now to the accompanying drawings in detail, the invention consists of a hair curler which is designated generally by the reference character 10 and embodies in its construction a flexible, resilient strip 12 consisting of an elongated cushion of air-foam rubber 14 and a waterproof casing 16 of thin, flexible sheet plastic material which completely encloses the cushion 14 and has free edges thereof suitably secured together, as exemplified at 18.

The strip 12 is folded in opposite directions along two transverse fold lines 20, 22 so as to afford continuous back, intermediate and front pads 24, 26 and 28, respectively, and the free end portion of the back pad 24 is secured as at 30 to the strip 12 at the fold line 22 between the intermediate pad 26 and the front pad 28, so that the pads 24, 26 constitute a pad unit 32 of double thickness, as is best shown in Figure 2.

The front pad 28, by virtue of the fold line 22, is swingable toward and away from the pad unit 32 so that a strand of hair 34 may be interposed between the pad unit 32 and the front pad 28 as shown in Figures 3 and 4.

A keeper element 36 comprises a tang 38 and an enlarged head 40 which is provided with an opening 42 and with an entrance slit 44 for this opening, as is best shown in Figure 1. This keeper element has the tang 38 thereof disposed in the free end portion of the back pad 24 between the cushion 14 and that portion of the plastic casing 16 which abuts the intermediate pad 26, so that the tang 38 is located substantially centrally in the pad unit 32 and is cushioned at both sides thereby, as illustrated in Figure 4.

The head 40 of the keeper element 36 projects outwardly from the back pad 24, as shown, and the tang is secured at 30.

A flexible elastic member 46 is provided with a loop 48 which is positioned on the strip 12 at the fold line 20 between the pads 24, 26, and the elastic member 46 is tied by a knot 50 to an ornamental bow 52 which also functions as a handle.

When the invention is placed in use, a strand of hair 34 is inserted between the pad member 32 and the front pad 28 and the front pad is closed upon the pad member as shown in Figure 4, whereupon the entire curler may be rotated several times so as to wind the strand of hair around the same. Then, by grasping the bow 52 and stretching the elastic member 46 across the front of the front pad 28, the curler may be secured in position on the strand of hair, the elastic member 46 being inserted into the opening 42 through the slit 44 in the head 40, so that the knot 50 engages the head and functions in the nature of a stop to prevent the elastic member 46 from being withdrawn from the opening 42.

Needless to say, the curler may be removed from the strand of hair by simply reversing the foregoing procedure.

It is believed that the advantages and use of the invention will be clearly apparent from the foregoing disclosure and, accordingly, further description thereof at this point is deemed unnecessary.

While in the foregoing there has been shown and described the preferred embodiment of this invention it is to be understood that minor changes in the details of construction, combination and arrangement of parts may be resorted to without departing from the spirit and scope of the invention as claimed.

Having described the invention, what is claimed as new is:

1. A hair curler comprising a flexible resilient strip folded in opposite directions along two transverse fold lines and providing a back pad, an intermediate pad and a front pad, a keeper element secured to and projecting longitudinally from the free end of the back pad, means se-

curing the free end of the back pad to the strip at the fold line between the intermediate and front pads, whereby the back and intermediate pads constitute a pad unit of double thickness, and a flexible elastic member attached to said pad unit at the fold line between the back and intermediate pads, said member extending across the front of said front pad and being separably attached to said keeper element, whereby a strand of hair may be sustained in position between the front pad and said pad unit.

2. The device as defined in claim 1 wherein said strip comprises an elongated cushion of foam rubber, and a waterproof casing of thin flexible sheet plastic material in which said cushion is disposed.

3. The device as defined in claim 1 wherein said keeper element comprises a tang disposed within said strip, and an enlarged outwardly projecting head provided on said tang, said head having an opening to receive said elastic member and an entrance slit for said opening, and a stop carried by said elastic member and engaging said head to prevent withdrawal of the elastic member from said opening.
